Fred. Weller

Theodore M. Smith,
INVENTOR
BY *Victor J. Evans*
ATTORNEY

UNITED STATES PATENT OFFICE.

THEODORE M. SMITH, OF NEW YORK, N. Y.

EDUCATIONAL DEVICE.

Application filed August 12, 1922. Serial No. 581,505.

To all whom it may concern:

Be it known that I, THEODORE M. SMITH, a citizen of the United States, residing at Bronx, in the county of Bronx and State of New York, have invented new and useful Improvements in Educational Devices, of which the following is a specification.

This invention relates to educational devices and more particularly to a device for teaching code systems and the like.

The principal object of the invention is the provision of a device whereby a person unfamiliar with the code system may very easily and quickly learn the same.

Another object of the invention is the provision of a device which comprises a stationary member having letters of the alphabet thereon and a movable member having code symbols and registering marks thereon, said marks in juxtaposition with relation to the code symbols, the registering marks adapted to be brought into registration with the letters of the alphabet on the stationary member.

A further object of the invention is the provision of a device which is simple of construction, cheap to manufacture and highly efficient for the purpose intended.

With these and other objects in view which will appear as the nature of the invention is better understood, the same consists in the detailed construction, combination and arrangement of parts, the essential features of which will be hereinafter more fully described, pointed out in the claims and shown in the accompanying drawing, in which:—

Figure 1, is a face view of the device.

Figure 2, is a top plan view of the same, and

Figure 3, is a vertical sectional view on the line 3—3 of Figure 1.

Referring more particularly to the drawings, the reference character 10 indicates a base or stationary member which may be made of any material and shape but in the present instance, is shown as square in configuration. The base 10 is slit longitudinally and stamped therefrom are strips 11, said strips projecting out from the face of the base 10 upon opposite sides thereof. The said strips 11, are spaced equidistant from the center and have suitable indicia 12, thereon in the nature of letters of the alphabet. In the drawings, only certain letters of the alphabet have been shown but it will

be understood that half of the letters may be arranged on the strip on one side and half on the strip of the other side. Movable members in the nature of disks 13 are mounted for rotation as at 14, upon opposite sides of the base, said disks 13 being interposed between the base 10 and the strips 11. The disks 13 have code symbols 15 radially arranged thereon and registering marks 16 in juxtaposition with the said symbols, the said registering marks adapted to register with the letters arranged on the strips 11. An arrow is shown at 17 which is adapted to register with the code symbols 15 when the registering marks 16, are brought into registration with the different letters of the alphabet.

For example, the letter (C) is represented by the code symbols (—.—) and it is desired to learn the code symbol of the letter (C), the disk 13 is revolved about its axis until the registering mark 16 is brought into registration with the letter (C) on the strip 11 as shown in Figure 1 of the drawings. It will be understood that both sides of the device are substantially alike, merely differing in the indicia thereon and the operation is the same in both instances.

Wherein there has been shown and described, a device showing indicia of the alphabet and their respective code symbols, it is to be understood that other suitable indicia may be substituted therefor and that no limitation is made to the indicia shown in the drawings but that changes, alterations and modifications as come within the claims may be resorted to when so desired.

What I claim as new is:—

1. A new article of manufacture comprising a base, strips stamped out from said base, and disks mounted for rotation on said base, said disks being interposed between said base and said strip.

2. A new article of manufacture comprising a base, strips stamped out from said base on opposite sides thereof and disks mounted for rotation on said base, said disks being interposed between said base and said strip.

3. A new article of manufacture comprising a base, strips stamped out from said base, said strips being spaced equi-distant from the center of said base on opposite sides thereof, and disks mounted for rotation on said base, said disks being interposed between said base and said strip.

4. An educational device comprising a base, strips stamped out from said base, suitable indicating indicia arranged on said strips, disks mounted for rotation on said base, said disks being interposed between said base and said strips indicating indicia on the disks significant to the indicating indicia on the strips, and registering marks in juxtaposition with the indicating indicia on the disks, adapted to be brought in registration with the indicating indicia on the strips as and for the purpose specified.

In testimony whereof I have affixed my signature.

THEODORE M. SMITH.
